UNITED STATES PATENT OFFICE.

ALBERT GEMÜNDER, OF COLUMBUS, OHIO.

PIANO-ACTION.

SPECIFICATION forming part of Letters Patent No. 269,405, dated December 19, 1882.

Application filed August 12, 1882. (No model.)

To all whom it may concern:

Be it known that I, ALBERT GEMÜNDER, a citizen of the United States, and a resident of Columbus, in the county of Franklin and State 5 of Ohio, have invented a new and valuable Improvement in Piano-Actions; and I do hereby declare that the following is a full, clear, and exact description of the construction and operation of the same, reference being had to the annexed drawings, making a part of this specification, and to the letters and figures of reference marked thereon.

Figure 1 is a partial vertical longitudinal sectional view. Fig. 2 is a detached perspective view of the pivoted lever, jack, spring, and their adjuncts; and Figs. 3 and 4 are detail views.

This invention relates to an improvement in piano-actions, and has for its object to reduce friction and simplify the construction of the action, and also obtain a high degree of elasticity, and to render the action compact and durable.

Referring by letter to the drawings, in which 25 a piano-action constructed in accordance with my invention is illustrated, A indicates the key, which is pivoted in a recessed block, B, by means of a pivot, C, journaled in the said block, and provided with a vertically-projecting pin, C', which passes up through the key. The upper end of this pin is screw-threaded, and a nut, D, and some suitable washer fitted thereon, whereby the key can be detached by first removing the said nut and washer.

30 E indicates the jack, which is pivoted in the free bifurcated end of a pivoted lever, F. The lower arm of this jack is forked and embraces a pin, G, attached to the key-lever. A nut, g, and a suitable washer are fitted upon this pin above the forked arm of the jack, and by adjusting said nut the height of the jack can be regulated.

The lifter H, which raises the lever carrying the jack, consists of a roller, h, journaled in 45 the lower bifurcated end of a stem, h', which latter is screw-threaded and passes through the lever F. By turning said lifter the lever and jack can be raised or lowered, as desired.

The mainspring I for repeating is bent into 50 U shape and secured to lever F, and to a slotted bar, i, through which the upper arm of the jack passes. The tension of the spring is va-

ried by means of a rod, K, pivoted at one end, and at its opposite screw-threaded end provided with a suitable nut.

In order to lessen friction, I provide either the jack or the under side of the arm of the hammer L with a roller, M, in the present instance the said roller being carried by the hammer-arm or handle and the jack acting 60 against the roller.

O indicates a movable back check for the hammer. This back check is sustained by a rod secured to a plate, P, which is slotted and fitted upon the key, and a set-screw passes 65 through the slot of said plate, whereby it can be adjustably secured upon the key, and thereby regulate the position of the back check with relation to the hammer.

Having thus described my invention, what I 70 claim is—

1. In a piano-action, the combination, with the key-lever A, provided with the vertical threaded pin C, having nut and washer, of the bifurcated bearing B and the removable 75 pivot C, substantially as specified.

2. In a piano-action, the combination, with the pivoted lever F, bifurcated at its free end, and the pivoted jack E in the forked end thereof, of the spring I, slotted arm i, the hammer-arm 80 L, roller M, and pivoted rod K, substantially as specified.

3. The lifter H, adjustably connected with a lever carrying the jack, and having a roller resting upon the key, substantially as specified. 85

4. In a piano-action, the combination of the pivoted key-lever A, the pivoted bifurcated lever F, the jack E, the lifter H, spring I, and slotted arm i, rod K, pin G, hammer L, and 90 friction-rollers M and h, constructed and operating substantially as specified.

5. The combination, with the pivoted lever F, of the spring I, the slotted bar i, and the jack passing through said bar, which is secured to one end of the spring, substantially 95 as described.

In testimony that I claim the above I have hereunto subscribed my name in the presence of two witnesses.

ALBERT GEMÜNDER.
